UNITED STATES PATENT OFFICE.

GEORGE T. TRUNDE, JR., OF CLEVELAND, OHIO, ASSIGNOR, BY MESNE ASSIGNMENTS, TO THE AUTOMATIC ELECTRIC SHOE POLISHING MACHINE COMPANY, OF BRYAN, TEXAS, A CORPORATION OF TEXAS.

SHOE-POLISHING MACHINE.

Application filed April 13, 1921. Serial No. 460,965.

To all whom it may concern:

Be it known that I, GEORGE T. TRUNDE, Jr., a citizen of the United States, residing at Cleveland, in the county of Cuyahoga and State of Ohio, have invented a certain new and useful Improvement in Shoe-Polishing Machines, of which the following is a full, clear, and exact description, reference being had to the accompanying drawings.

This invention relates to shoe polishing machines and is primarily concerned with the construction of a semi-automatic machine, wherein a power driven rotary brush is mounted so as to be moved universally by an operator, for cleaning and polishing shoes.

The usual practice in semi-automatic shoe polishing machines is to construct a polishing mechanism, which may be employed by an operator for polishing shoes, after he has manually applied paste thereto. In a machine of this type it is desirable to obtain a brush, which may be universally manipulated, without causing undue physical strain upon the operator. Accordingly, it is essential that the weight of the moving parts be supported in such manner, that the operator is free to guide the brush over the various parts of the shoe, without being compelled to carry the weight of the operating mechanism. It is also desirable that the driving mechanism be located below the brush to prevent its interfering with the clothing of the customer.

One of the objects of my invention therefore, is the provision of a polishing machine wherein the brush is universally movable and is driven from below by comparatively light, readily shiftable mechanism.

Another object is the provision of a machine which may be employed in connection with existing shoe polishing stands, or which may be installed therein without requiring expensive alterations.

Further features include the provision of a machine which may be operated either by an individual motor, or by connection with a line shaft from which a number of brushes may be operated.

In accomplishing the above objects I provide a rotary brush which is normally positioned adjacent the shoe rests of a shoe

polishing stand, and which is adapted to be supported and driven by a mechanism beneath the stand. The particular arrangement of the mechanism for securing universal movement of the brush, will be hereinafter set forth in the following description which relates to the drawings, and the essential characteristics of my invention will be set forth in the claims.

In the drawings, Fig. 1 is a longitudinal section through a shoe polishing machine, embodying the features of my invention. Fig. 2 is a transverse section taken on the line 2—2 of Fig. 1. Fig. 3 is an end elevation taken from the front of the shoe polishing stand. Figs. 4 and 5 are figures showing enlarged side and end views of the brush operating mechanism.

My invention contemplates in general the construction of a shoe polishing machine which is adapted for use in connection with existing stands, and which is employed for polishing shoes after an operator has applied paste thereto. The mechanism which I prefer to employ for securing universal movement of the brush is shown and described in connection with a single stand, but it is to be understood that such mechanism is operable when used in connection with a series of stands which are arranged in a row, and which may be operable from a single line shaft.

Referring now to the drawings and designating the parts shown therein by the use of reference characters, 10 represents the base of a shoe shining stand having walls 11, for supporting a chair platform 12 and a foot platform 13, respectively. The stand may be constructed in accordance with the customary methods but the bracing means must be such as to permit the freedom of movement of the mechanism which will be hereinafter described.

To operate the polishing brush 15, I may provide a motor 16 which is rigidly supported on the base and on the interior portion of the stand. This motor is shown as having the axis 17 thereof positioned obliquely to the front of the stand and as carrying a driving pulley 18 on one end of the armature shaft.

Above the motor and rigidly mounted on the stand, I provide a bracket 19 on which

an idler wheel 20 is supported as at 21. Pivotedly mounted on this bracket, as at 22 and 25, I also provide a pair of arms 23 and 24 respectively, which arms are in vertical alignment and constitute part of a four-bar linkage system, the purpose of which will be hereinafter set forth. The ends of the arms 23 and 24 may terminate in inclined brackets 26 and 27 respectively, and support guide 10 pulleys 29 and 30.

The outermost ends of the arms 23 and 24 are arranged to carry on horizontal pivots brackets 31 and 32 which are shown as extending outwardly toward the front of the 15 stand and as comprising supporting members for a vertical shaft 33. Mounted on the shaft 33, I provide a driven pulley 34 which is rotatably connected with a pulley 35. The pulley 34 is rotated by the belt 36 which 20 passes around the driving pulley 18 over the guide pulley 30, around the driven pulley 34, back and under the guide wheel 29, over the idler wheel 20 and thence back to the driving wheel 18.

25 The four-bar linkage system comprises as above set forth, the arms 23 and 24, bracket 19 and the shaft 33. This linkage system provides for vertical movement of the shaft 33 about the pivotal points 22 and 25 and 30 enables such movement to occur, while the shaft 33 remains in a vertical position at all times. The downward movement due to gravity may be counter-acted by a tension spring 37 while complete movement in 35 either direction may be limited by the upper and lower stops 38, 39 on the retaining bar 40. Any movement by the four-bar linkage system enables the belt 36 to operate continuously, by reason of the fact that 40 the centers of the guide pulleys 29 and 30 are equidistant at all times.

45 Pivotedly mounted on the shaft 33, and preferably intermediate the brackets 31 and 32, I provide an arm 41 which may be in the form of a frame, that carries a shaft 42 and acts as a cantilever in supporting the brush 15. To transmit motion from the shaft 33, to the shaft 42, I provide a belt 43 which connects the pulley wheel 35 with the wheel 50. This wheel is rigidly connected with the shaft 42 and is therefore operative irrespective of the position of the arm 41 relative to the shaft 33. The ends of the arm 41 50 preferably terminate in a forked member having the projecting portions 45 and 46 which constitute the bearings for the shaft 42.

60 Extending outwardly from the arm 41, and pivotally mounted on the shaft 42, I provide a brush carrying arm 47, which may also be constructed in the form of a rectangular frame, and in a manner similar to the construction of the arm 41. The end of the frame 47, which is mounted on the shaft 42, may comprise a bifurcated member hav-

ing the portions 48 and 49 embracing the shaft 42 and positioned intermediate the bearing portions 45 and 46 on the arm 41. The brush carrying frame supports a rotary shaft 50 which shaft may receive rotation 70 through the bevel gears 51 and 52 respectively.

Referring now to Fig. 4, it will be seen that the extreme outer end of the shaft 50 terminates in a bevel gear 53, while the end 75 of the frame 47 acts as a supporting means for the brush holder 54. This brush holder may be rotatably mounted within the end of the frame 47 by means of a flange 55, which extends into a recess in the end of the 80 frame, and is held thereagainst by a split ring 56. A shaft 57, to which the brush is rigidly secured, is rotatably supported by the holder and is adapted to be rotated by means of a gear 58 which meshes with the 85 gear 53. The construction of the brush holder enables the brush to be rotated on its own axis and at the same time to be revolved about the axis of the shaft 50. To prevent the weight of the holder from 90 revolving the brush however, I provide a spring pressed plunger 59 which is adapted to engage suitable recesses 60, in the flange 55, and to retain the brush holder in any 95 selective position.

To enable an operator to manipulate the brush 15, I provide a handle 61, on the brush holder, which handle is conveniently positioned so as to permit the brush to be reciprocated or revolved while it is being rotated. 100 The center of the handle is preferably on a line with the axis of the shaft 50, so that the brush may be readily revolved about the axis of the shaft, without placing a strain upon the wrist of the operator. Reciprocating and oscillating movement of the brush may be obtained by buckling the arms 41 and 47 about the shaft 42, as shown in Fig. 2, while vertical movement thereof may be obtained by raising or lowering the entire 110 mechanism about the pivot points 22 and 25 respectively. The amount of vertical movement thus obtained, is governed by the distance between the stops 38 and 39. Additional movement may be obtained, however, by revolving the brush about the axis of the shaft 50; this additional movement being sufficient to bring the brush into contact with all parts of the shoe. While I have shown the brush in a position intermediate the foot rests 62, it is obvious that the supporting arms may be buckled inwardly, and the brush swung around the back of the foot rests to bring it into contact with the outer side of each shoe. 115

120 The operation of my machine is as follows:—Assuming that a customer is seated in the chair 63, and that the operator has applied paste to the shoes, then a switch— 125 not shown,—is closed and the motor 16 130

thereby set in operation. Immediately the brush 15 is rotated, such rotation being transmitted through the belts 36 and 43 respectively, and thence through the beveled 5 gearing on the shafts 42, 50 and 57 respectively. During the paste applying operation, the frames 41 and 47 are buckled inwardly, and the brush 15 is pushed backwardly, so that the operator is allowed freedom of movement for applying paste to the 10 customer's shoes. After the brush is set in rotation, however, then the operator seizes the handle 61 and pulls the brush forwardly, and reciprocates it by pivoting the frames 15 41 and 47 about the shafts 33 and 42 respectively. To obtain vertical movement, the brush 15 is raised or lowered, either by pivoting the entire mechanism about the points 22 and 25, or by revolving the brush 20 about the axis of the shaft 50. The construction of the mechanism is such that the horizontal, vertical and revolving motion may be accomplished simultaneously or each motion may be produced independently of 25 the other motions. After the polishing operation is completed the brush may be pushed backwardly beneath the stand and the current disconnected, whereby the mechanism is in readiness for a succeeding 30 customer.

From the foregoing description it will be seen that I have provided a semi-automatic shoe polishing machine, which provides for universal movement of a polishing brush, 35 while the brush is rotating at a speed sufficient for producing a satisfactory polish. This construction enables the entire polishing operation to be effected without causing undue strain upon the arm of the operator 40 and without endangering either himself or the person whose shoes are being cleaned. Furthermore, it will be seen that I have avoided any shafts or other mechanism coming to the brush from above and have provided a mechanism which is capable of being 45 installed in existing stands. My mechanism is comparatively simple in construction, and is adapted for use in installations embodying one or more stands.

Having thus described my invention, I 50 claim:

1. A shoe polishing machine having in combination a foot rest, a brush, means for rotating the brush, and means including a 55 linkage system and a brush holder rotatably mounted thereon for supporting said brush independently of the foot rest and from below the horizontal plane through said rest and in such a manner that the brush may be universally moved by the operator, and a handle connected to said support in the vicinity of the brush.

2. A shoe polishing machine having in combination a stand, a brush, means for rotating the brush, mechanism for support- 60

ing the brush in various operative positions with reference to the stand while allowing it a universal movement, and a handle for the brush on the opposite side thereof from the support therefor.

3. A shoe polishing machine having in combination a stand, shoe supports, a brush, means including a rotatable shiftably carried holder for supporting the brush beneath the stand, whereby universal movement 70 of the brush may be obtained, and means for rotating the brush, said last mentioned means being positioned below the shoe supports, both the brush support and the driving means for the brush being 75 mounted independently of the shoe supports.

4. In a shoe polishing machine the combination with a stand, of a pair of shoe supports, a brush positioned beneath the stand and arranged for universal movement with relation to the supports, a source of power for rotating the brush, the source of power being positioned within the stand, and an operator's handle connected with the brush on the side thereof opposite the support therefor.

5. In combination, a brush, means for rotating the brush, means including a four-bar linkage system for supporting the brush 95 and for permitting movement thereof in one plane and means, carried by the four-bar linkage, for permitting movement of the brush in another plane.

6. In combination, a brush, means for rotating the brush, means for providing universal movement of the brush, said latter means comprising a four-bar linkage system and arms pivotally connected with said links.

7. In combination, a brush, means for rotating the brush, means for enabling said brush to be moved in a vertical plane, means for enabling said brush to be swung in a horizontal plane, and means for enabling the brush to be bodily revolved in substantially the plane of its axis of rotation.

8. A shoe polishing machine having in combination, a brush, a revoluble brush-holding member, and a spring detent associated with said member for selectively retaining the brush in various positions of revolution.

9. A shoe polishing machine having in combination a stand, a brush, means for rotating the brush, means extending outwardly from the stand and adapted to carry the brush, said last mentioned means being arranged to permit the brush to be revolved about an axis at right angles to the axis of rotation, and means for selectively retaining the brush in various positions of revolution.

10. In combination, a stand, extensible arms carried by the stand, a drive shaft 130

carried by one of the arms, a brush adapted to be rotated by said shaft and to be revolved about the axis thereof, a brush holding member and a spring detent, and a recess on which it may seat intermediate said member and the shaft carrying arm for normally restraining the member against revolution.

11. In combination, a stand, extensible members carried by the stand and extending outwardly therefrom, a brush mounted on the end of one of said members, means for rotating the brush, said means comprising an endless belt extending from one of said members to another of said members, and a drive shaft, means for permitting the brush to be revolved about the axis of said drive shaft, and yielding means for normally retaining the brush in one position.

12. In a shoe polishing machine, the combination with a stand, of a brush, extensible supporting means pivoted to the stand and extending outwardly therefrom, said means comprising a four-bar linkage system, an arm pivoted thereto, a brush carrying frame pivoted to said arm, a drive shaft carried by said frame, a brush holding bracket adapted to be revolved about the axis of said shaft, and means for rotating the brush.

13. A shoe polishing machine having in combination a brush, a motor for rotating the brush, extensible means adapted to support the brush, said means comprising a linkage system and a plurality of pivoted arms carried thereby, means for transmitting motion from the motor to the brush, said last mentioned means including a pair of guide pulleys mounted on the movable members on said linkage system, a driven

pulley, and a belt connecting the motor with said pulleys.

14. A shoe polishing machine having in combination a stand, a brush, a motor, a pulley thereon, a bracket carried by the stand, means including a four-bar linkage system, pivoted members carried thereby, and a brush rotatably carried by said members for permitting universal movement of the brush, an idler wheel carried by the bracket, guide wheels and a driven wheel associated with the four-bar linkage system and a belt connecting said wheels.

15. In a shoe polishing machine, the combination of a foot rest, a brush, extensible supporting means for the brush, comprising a linkage system, an arm pivoted thereto, a brush carrying frame pivoted to said arm, a drive shaft carried by said frame, a brush holding bracket having a handle thereon adapted to be revolved about the axis of said shaft, and bevel gearing between the shaft and the brush.

16. In a device of the class described, the combination of a brush, a shaft therefor extensible supporting means for the shaft and brush, said means comprising a linkage system for permitting the movement of the brush in a vertical plane, an arm pivoted to said system on a vertical pivot, a second arm pivoted to the first arm on a vertical pivot, a bracket swiveled to the second arm on a horizontal axis, a shaft journaled in the second arm, bevel gearing connecting the two shafts, and means for driving the shaft in the arm irrespective of its vertical position.

In testimony whereof, I hereunto affix my signature:

GEORGE T. TRUNDLE, JR.
